UNITED STATES PATENT OFFICE

93,724

DESIGN FOR A BOTTLE

Abraham Lincoln Key, Great Kills, Staten Island, N. Y., assignor to American Commercial Alcohol Corp., Pekin, Ill., a corporation of Maryland

Application September 1, 1934, Serial No. 53,137

Term of patent 14 years

To whom it may concern:

Be it known that I, ABRAHAM L. KEY, a citizen of the United States, residing at Great Kills, Staten Island, in the county of Richmond and State of New York, have invented a new, original, and ornamental Design for a Bottle, of which the following is a specification, reference being had to the accompanying drawing forming part thereof.

I claim:

The ornamental design for a bottle, as shown.

ABRAHAM LINCOLN KEY.
